UNITED STATES PATENT OFFICE.

FERDINAND CHARRON AND LÉONCE GIRARDOT, OF PARIS, FRANCE.

PULVERIZING-CARBURETER FOR PETROLEUM-MOTORS.

SPECIFICATION forming part of Letters Patent No. 733,695, dated July 14, 1903.

Application filed March 22, 1902. Serial No. 99,513. (No model.)

To all whom it may concern:

Be it known that we, FERDINAND CHARRON and LÉONCE GIRARDOT, citizens of the Republic of France, residing at 45 Avenue de la Grande Armée, Paris, in the Republic of France, have invented certain new and useful Improvements in the Construction of Pulverizing-Carbureters for Petroleum-Motors, of which the following is a specification.

It is well known that to obtain good carburetization it is desirable to prevent the cooling produced in the jet or spray carbureters through the expansion of the gas. According to this invention such cooling is prevented by constructing the carbureter with a double wall or jacket in order that the hot water coming from the motor-jacket may circulate in the jacket of the carbureter previously to passing to the radiator. By this means the zone where the mixture of air and petrol is produced is kept at a favorable temperature for the carburetization, and at the same time the water coming from the jacket of the motor is more cooled. To attain our object, it was necessary to take into consideration that the carbureter has to be easily unmountable, so as to allow access to its interior, and has also to be removably joined to the air-conducting pipes, to the petrol-feeding pipe, and to the pipe leading the combustible mixture to the motor. Furthermore, it is absolutely necessary to render the infiltration of water in the jacket of the carbureter quite impossible; otherwise the carburetization would be immediately stopped.

The annexed drawings represent a form of construction of our hot-water-jacketed carbureter.

Figure 1 is a longitudinal section on line 1 2 of Fig. 2. Fig. 2 is a plan. Fig. 3 is a vertical section on line 3 4 of Fig. 2. Fig. 4 is a horizontal section on line 5 6 of Fig. 1.

The brass body of the carbureter comprises three separately-cast parts, each in one piece. These parts are, first, the "carbureter," properly called, *a*, with its air-inlet pipe *a'*; secondly, the tubular cap *b*, which closes at the outside and top part of the water-chamber surrounding the carbureter-chamber and constitutes at the same time the side or wall of the jacket surrounding the upper part of the air-inlet pipe, and, thirdly, the flange-joint

c, which closes at the top part the water-chamber surrounding the air-inlet pipe and permits of the fixing of the pipe which directs the air to the carbureter. The drawings show clearly how these different parts are fixed and show that no communication can take place between the spaces where the gases circulate and the water-chamber. 55

The apparatus is fixed on a plate *g*, in which is made the bore *o*, through which the petrol or the like passes to the carbureter-nozzle from an ordinary reservoir with constant level, and it is completed by the ordinary devices used in carbureters of this kind, the nozzle *h* and the cone *p*, which, as shown on the drawings, may be in one piece with the stopper *r*, which closes the carburetization-chamber at the top. The air arrives, therefore, in 70 the carbureter by the pipe *a'*, the petrol through nozzle *h*, and the combustible mixture goes to the motor through the pipe *s*. The hot water of the circulating system enters the chamber-jacket at the top part at *t* 75 and passes out at the lower part at *v* after having heated the carbureter.

Having now described our invention, what we claim as new, and desire to secure by Letters Patent, is—

A jet or spray carbureter for petroleum-motors comprising a carbureter-body *a* with a hot-water jacket, in combination with a tubular casing *b* which closes at the top the water-chamber surrounding the body of carbureter and which forms at the same time the wall of the jacket surrounding the top part of the air-inlet pipe *a'*, a joint-flange *c* which closes at the top the water-chamber surrounding the air-inlet pipe and which allows of fixing to the carbureter the air-inlet pipe, a plate *g* to which is secured the body of the carbureter and in which is provided a petroleum-inlet conduit *o*, and a nozzle *h* screwed in the plate *g* and leading to the carburetization-chamber, substantially as and for the purpose set forth. 85

In witness whereof we have hereunto set our hands in presence of two witnesses.

FERDINAND CHARRON.

LÉONCE GIRARDOT.
